BATTERY POWERED ILLUMINATING MIRROR

Donald P. Stahl, North Bellmore, N.Y., assignor to
Telecommunications Industries, Incorporated, Farming-
dale, N.Y.

Filed May 25, 1970, Ser. No. 23,117

Term of patent 14 years

Int. Cl. D12—16; D6—06
U.S. Cl. D14—6

The figure is a perspective view of a battery powered illuminating mirror embodying my new design.

The visor and clips, shown in broken lines, are included for illustrative purposes only.

The bottom, rear and side opposite to the one shown are flat and plain.

I claim:

The ornamental design for a battery powered illuminating mirror, as shown and described.
